UNITED STATES PATENT OFFICE.

CHARLES W. ELLIOTT, OF NORTHFORK, WEST VIRGINIA.

BOTTLING-MACHINE.

No. 856,135.

Specification of Letters Patent.

Patented June 4, 1907.

Application filed December 26, 1905. Renewed February 25, 1907. Serial No. 359,126.

To all whom it may concern:

Be it known that I, CHARLES W. ELLIOTT, a citizen of the United States, residing at Northfork, in the county of McDowell and State of West Virginia, have invented certain new and useful Improvements in Bottling-Machines, of which the following is a specification.

Bottling machines, as heretofore generally constructed, depend upon displacement of the air from the bottles during the filling operation by means of the liquid entering the same, and as a result valuable time is consumed and a considerable quantity of the liquid is lost.

The purpose of the present invention is to combine with a bottling machine means for exhausting the air from the bottle preliminary to filling the same with the result that no liquid or gas is wasted and no time lost, the operation being hastened and greatly facilitated.

The invention contemplates combining with the filler head of a bottling machine, means for exhausting the air from the bottle, said means embodying a valve which is adapted to be operated by the usual handle employed for sealing or closing the bottle after it has been filled.

For a full description of the invention and the merits thereof and also to acquire a knowledge of the details of construction of the means for effecting the result, reference is to be had to the following description and accompanying drawings.

While the invention may be adapted to different forms and conditions by changes in the structure and minor details without departing from the spirit or essential features thereof, still the preferred embodiment is shown in the accompanying drawings, in which:

Figure 1 is a perspective view of a bottling machine embodying the invention. Fig. 2 is a sectional detail of the filler head on a larger scale, showing the invention applied thereto. Fig. 3 is a front view of the upper portion of the machine showing the parts on a larger scale.

Corresponding and like parts are referred to in the following description and indicated in all the views of the drawings by the same reference characters.

The bottling machine illustrated is of ordinary construction and has been selected because illustrative of the type to which the in-

vention in practice has been applied. It is to be understood that the invention may be readily adapted to any make or style of machine.

60

In the machine shown in the accompanying drawings, the numeral 1 designates the filler head which is carried by means of a yoke 2 vertically movable and operatively connected with a treadle mechanism so as to 65 be actuated by foot power. The filler head, yoke and actuating means are of well known construction and are illustrated simply to show the application of the invention.

The filler head 1 is provided with a cup 3 70 adapted to receive the upper end of the bottle and within said cup is located a gasket 4 of rubber or like material to insure the formation of a tight joint between the bottle and the filler head. Coupling ends 5 and 6 75 project from the filler head, preferably in diametrically opposite directions and pipes 7 and 8 are connected therewith. The pipe 8 connects with the means for supplying syrup, water and gas or the like with which the bottles are to be filled. The pipe 7 connects with an air exhausting means. In the preferable arrangement a vacuum chamber 9 is employed and the pipe 7 makes connection therewith, said chamber 9 being connected to 80

a vacuum pump 10 or like appliance for exhausting the air from the chamber 9. A valve is interposed in the length of the pipe 7 and is arranged preferably adjacent to the filler head 1 and controls the communication 85 between the filler head and the air exhausting means or vacuum chamber 9. The valve is preferably of the self-closing type and embodies a casing 11 and a reciprocating gate 12, the latter being normally acted upon by 90 means of a spring 13 interposed between its inner end and said valve casing. An opening 14 provided in the valve, gate or closure 95

12 is normally out of register with the passage establishing communication between the 100 filler head and pipe 7. When the valve, gate or like part 12 is pressed inward, the opening 14 is caused to register with the pipe 7 and coupling 5, thereby establishing communication between the filler head and the 105 air exhausting means, whereby the air from the bottle in position is exhausted preliminary to the filling operation.

The bottle closer 15 operates through the filler head, yoke and a stuffing box applied to 110 said yoke and is connected at its upper end to the usual operating handle or lever 16, which

is connected by a link 17 to an arm 18 fast to or formed with the yoke 2. The valve interposed in the length of the pipe 7 is adapted to be controlled by means of the lever or handle 16, and for this purpose a rod or arm 19 is connected at one end with said lever or handle 16 and its opposite end is arranged to come in contact with the valve or closer 12 so that upon depressing the outer end of the lever or handle 16, the valve 12 will be pressed upon to effect opening thereof. Upon removing the pressure from the handle or lever 16, it will be returned to normal position by means of a spring 20 surrounding the bottle closer 15 and normally exerting an upward pressure thereon. As the lever or handle 16 returns to normal position, the valve 12 likewise assumes a normal position by the action of the spring 13, thereby cutting off the air exhausting means from the filler head.

For convenience and simplicity of construction the arm 19 is utilized as connecting means between the lever 16 and the bottle closer 15, the head of the latter being forked 25 to receive the lever 16 and the upper end of the arm 19 passing through coinciding openings in the lever and the embracing parts of the bottle closer head.

The operation of the invention is as follows: A bottle being placed in position in the usual manner and the filler head closed thereon by operating the treadle mechanism, the outer end of the handle or lever 16 is depressed, thereby opening the valve 12 30 and establishing communication between the bottle and the air exhausting means through the filler head and intermediate connecting means. The air is instantly exhausted from the bottle, after which the lever or handle 16 35 is released and the valve 12 closes in the manner herein stated. The syrup, water and gas or other carbonated liquid or beverage to be supplied, is turned on in the usual manner and flows into the bottle through 40 the filler head in the accustomed way, and 45 after the bottle has been filled, it is closed by

operating the lever or handle 16 or in any way commonly provided and depending upon the character and peculiar type of machine equipped with the invention.

From the foregoing it will be understood that the air contained in a bottle to be filled, is not displaced or blown off by the inflowing liquid, but being exhausted from the bottle, preliminary to the filling operation, obviates the usual wasting of the material and greatly facilitates and expedites the filling operation and consequently materially increases the capacity of the bottling machine to which the invention is applied.

Having thus described the invention, what is claimed as new is:

1. In combination, a filler head, a bottle closer operating therethrough, an air exhausting pipe connected with the filler head, a self closing valve arranged in the length of the exhaust pipe adjacent to the filler head, an operating lever and an arm independent of and exterior to the filler head for operating the exhaust valve upon actuating the operating lever and connected with the latter and with the bottle closer.

2. In combination, a filler head, a bottle closer operating therethrough, an air exhausting pipe connected with the filler head, a self closing valve arranged in the length of the exhaust pipe adjacent to the filler head, and operating across said pipe parallel with the bottle closer, an operating lever for the bottle closer, and an arm independent of and exterior to the filler head for opening the exhaust valve upon actuating the operating lever and connected with the latter and with the bottle closer and serving as connecting means between the said lever and bottle closer.

In testimony whereof I affix my signature in presence of two witnesses.

CHARLES W. ELLIOTT. [L. s.]
